UNITED STATES PATENT OFFICE.

MAURICE C. RYPINSKI, OF YONKERS, NEW YORK, ASSIGNOR TO BRANDES LABORATORIES, INC., OF NEWARK, NEW JERSEY, A CORPORATION OF NEW JERSEY.

DESIGN FOR A LOUD-SPEAKER CABINET.

Application filed December 31, 1926. Serial No. 20,256. Term of patent 14 years.

To all whom it may concern:

Be it known that I, MAURICE C. RYPINSKI, a citizen of the United States of America, residing at Yonkers, in the county of Westchester and State of New York, have invented a new, original, and ornamental Design for a Loud-Speaker Cabinet, of which the following is a specification, reference

being had to the accompanying drawing, forming part thereof.

The figure is a perspective view showing my design of loud speaker cabinet.

I claim:

The ornamental design for a loud speaker cabinet as shown.

MAURICE C. RYPINSKI.
